(57) **CLAIM**

The ornamental design for a display screen having a graphical user interface, as shown and described.

DESCRIPTION

The patent or patent application file contains at least one drawing executed in color. Copies of this patent or patent application publication with color drawing(s) will be provided by the Office upon request and payment of the necessary fee.

Portions of the disclosure of this patent document contain material to which claims for copyright are made. The copyright owner has no objection to the reproduction of the patent document or the patent disclosure, as it appears in the U.S. Patent Office records, but reserves all other copyright rights whatsoever.

The FIGURE is a front view of a display screen having a graphical user interface.

The broken-line perimeter illustrates a display screen and forms no part of the claimed design.
